ELECTRIC MOTOR CONTROL

Ralph G. Lockett, Wauwatosa, Wis., assignor to
 Cutler-Hammer, Inc., Milwaukee, Wis., a corporation of Delaware

Application October 12, 1935, Serial No. 44,643

19 Claims. (Cl. 172—240)

This invention relates to improvements in electric motor control. The invention relates more particularly to a control system for a reversible electric motor driving a rotatable load of such character as to be self-reversing after coasting thereof to zero speed as an incident to interruption of the motor circuit connections.

An object of the invention is to provide novel means for timing completion of reverse circuit connections for a motor driving a load of the character aforementioned, whereby excessive speed of the motor at the moment of completion of the reverse circuit connections is avoided.

Another object is to provide means of the aforementioned character which is simple, efficient and inexpensive.

A more particular object is to provide novel means for controlling reversing of a motor driving a load comprising a substantially cylindrical container rotatable upon a horizontal axis, and which container is partially filled with loose or amorphous material.

Another object is to provide a control system of the aforementioned character having the desired features of manual and automatic control.

Other objects and advantages of the invention will hereinafter appear.

The accompanying drawing illustrates schematically and diagrammatically an embodiment of the invention which will now be described,—it being understood that the embodiment illustrated is susceptible of modification as to certain details thereof without departing from the scope of the appended claims.

I have illustrated my invention as applied to the control of a reversible motor driving a cylinder or container which is rotatable upon a horizontal axis,—such as is used in the malting industry to dry or otherwise treat large quantities of loose or amorphous material such as cereal or grain. As will be apparent to those skilled in the art, however, the invention is likewise applicable to the control of reversible motors driving loads of other material of a loose or amorphous character,—as for instance the cylindrical containers used by the laundry industry for clothes washing and/or drying machines.

In a device of this character it is desired to rotate the cylinder a predetermined number of times in one direction,—any suitable or desired timing means, such as a limit switch of the double throw type, being employed to effect interruption of the energizing circuit of the active reversing switch. Heretofore it has been customary to allow the cylinder to coast for a short period of

time as preselected by adjustment of a timing relay,—the timing relay when operated being adapted to bring in the other reversing switch to effect reversal of the motor and the cylinder driven thereby. However, it has been found in practice that the machine comes to zero speed quite rapidly due to the weight of the cereal or similar loose or amorphous material which builds up inside of the drum or cylinder. In many instances it was found that the equipment actually reversed before the reversing contactor was closed by the timing relay,—with the result that very often the motor was driven over-speed by the cylinder. In such cases when the motor is energized and thereafter brought down to normal speed there is quite a shock upon the machinery,—and it is even likely that the motor may be driven temporarily at such an excessive speed as to injure or wreck the same mechanically.

From the foregoing it will be apparent that it is very important that the reversing contactor be brought in at a point close to zero speed of the cylinder; or, in other words, immediately after zero speed has been attained by the cylinder, and before any substantial degree of reverse rotation thereof by its self-reversing action aforementioned. A fixed timing for the coasting period obviously is not suitable because the load varies considerably from time to time, and the length of the coasting period desired varies correspondingly. The aforementioned defects and disadvantages of prior devices are overcome or avoided by my invention.

Referring to the drawing, the numeral 5 designates a cylinder or drum which is rotatable upon a horizontal axis as by means of a reversible electric motor 6. Motor 6 is preferably of standard squirrel cage type, and suitable speed-reducing gearing 7 is preferably interposed between the armature shaft 8 thereof and the shaft 9 of cylinder 5. Cylinder 5 is provided with an opening, the door or closure for which is shown diagrammatically at 10, to provide for partially filling the cylinder with cereal or similar loose or amorphous material; as, for instance, to the level indicated by the dotted line 11. Motor 6 is adapted to be supplied with current from a suitable source of supply, represented by lines L¹, L² and L³, through the medium of a pair of electromagnetically operable reversing switches 12 and 13. The operating windings 12^a and 13^a of switches 12 and 13 are respectively subjected to control by the limit switches 14 and 15,—the latter being

35

40

45

50

55

60

mechanically connected, as by means of the pivoted link 16, to insure joint operation thereof.

The shaft 9 of cylinder 5 is provided with a threaded extension 9^a which is adapted to cooperatively engage a pair of traveling nuts 17 and 18,—a guide rod or plate 19 being adapted to restrain said nuts against rotation. The arrangement is such that upon a predetermined number of revolutions of cylinder 5 in one direction the 10 nut 18 will engage switch 15 to effect opening thereof, while the link 16 acts to simultaneously effect closure of switch 14,—an over-center spring 20 being provided to insure snap movements of switches 14 and 15 between opposite 15 extreme positions thereof. Upon reversal of the direction of rotation of cylinder 5 nuts 17 and 18 will travel toward the left, until nut 17 engages switch 14 to effect opening thereof,—link 16 acting in the manner aforescribed to simultaneously 20 effect closure of switch 15.

One or the other of the limit switches 14 and 15 is initially rendered effective for completing an energizing circuit for the winding 12^a or 13^a respectively associated therewith by closure simultaneously of a pair of normally open electromagnetically operable relays 21 and 22; relay 21 having an operating winding 21^a and sets of contacts 21^b, 21^c, and relay 22 having an operating winding 22^a and sets of contacts 22^b, 22^c. Energization and closure of relays 21 and 22 is effected by momentary closure of a normally open push button switch 23.

Thus with the several parts in the positions thereof illustrated, the equipment may be started 35 in operation by momentarily depressing the push button 23. This completes an energizing circuit for the winding of relay 21, which circuit may be traced from line L¹ by conductors 24 and 25 through contacts 23^a, 23^b and 23^c of switch 23, by 40 conductor 26 through the winding 21^a of relay 21, and by conductors 27 and 28 to line L³. The normally open contacts 21^b, 21^c of relay 21 are thus closed. At the same time an energizing circuit is completed for the winding of relay 22, which 45 circuit may be traced from line L¹ by conductors 24 and 25 through contacts 23^a, 23^b and 23^c of switch 23, by conductors 29 and 30 through the contacts of a normally closed push button switch 31, by conductor 32 through the winding 22^a of 50 relay 22, and by conductors 33 and 34 to line L³. The normally open contacts 22^b and 22^c of relay 22 are thus closed.

An energizing circuit for the operating winding of reversing switch 13 is thus completed, 55 which circuit may be traced from line L¹ by conductors 24 and 34 through contacts 22^c of relay 21, by conductor 35 through contacts 21^c of relay 21, conductor 36 through limit switch 15, conductor 37 through said winding 13^a, and by conductors 38 and 39 to line L³, whereupon the contacts 13^b, 13^c, 13^d of switch 13 are closed to provide for operation of motor 6 and container 5 in a direction such as to cause movement of nut 18 toward the right.

60 In accordance with my invention there is provided a switch 39 comprising an oscillatable contactor 39^a and a pair of contacts 39^b, 39^c to be selectively engaged thereby,—depending upon the direction of operation of motor 6 and container 5 driven thereby. For this purpose the armature shaft 8 of motor 6 is shown as provided with an extension 8^a to which a pulley or wheel 39^d is keyed or otherwise rigidly secured. Extending 65 around and frictionally engaged with wheel 39^d is a belt or strap 39^e, the opposite ends of which

are rigidly attached to contactor 39^a on opposite sides of the point of pivotal support of the latter. Suitable means (not shown) are provided for insuring the desired degree of tension of belt 39^e against wheel 39^d. A switch of the general character illustrated at 39 is shown and described in detail in Patent No. 1,964,199, granted June 26, 1934, to C. T. Evans.

It is to be understood that with motor 6 and container 5 operating in a direction to effect movement of nut 18 toward the right (as indicated by the arrows on shafts 8 and 9) the contactor 39^a of switch 39 will be engaged with contact 39^b,—thus providing for the winding 13^a of reversing switch 13 a maintaining circuit which 15 shunts the contacts 21^c of relay 21. It is therefore obvious that after momentary depression of push button 23 the same may be released to permit de-energization and opening of relay 21,—it being noted that the energizing circuit for relay 20 22 when completed is self-maintained by a circuit which may be traced from line L¹ by conductors 24 and 34 through contacts 22^c, 22^b of relay 22, by conductors 40 and 30 through switch 31, conductor 32 through the winding 22^a, and 25 by conductors 33 and 28 to line L³.

The aforescribed maintaining circuit for the winding 13^a of switch 13 may be traced from line L¹ by conductors 24 and 34, through contacts 22^c of relay 22, conductor 35 through contactor 39^a 30 and contact 39^b of switch 39, conductors 41 and 36 through limit switch 15, conductor 37 through said winding 13^a, and conductors 38 and 39 to line L³.

In view of the fact that contactor 39^a is normally in one or the other of its extreme positions, it is obvious that if desired the relay 21 might be entirely omitted. Relay 21 has been shown herein as providing means for positively insuring ability to start the system in operation at will, 40 even though the contactor 39^a of switch 39 should accidentally remain in an intermediate position out of engagement with both contacts 39^b, 39^c after the last preceding stopping operation. Stopping of the system may be effected at will at 45 any time by merely depressing the push button 31 momentarily, thus interrupting the maintaining circuit for the winding 22^a of relay 22.

Pending depression of push button switch 31 50 motor 6 will operate under the conditions aforescribed until nut 18 in its movement toward the right engages and opens the limit switch 15, with consequent de-energization of the winding 13^a of reversing switch 13. Upon opening of limit switch 15 the limit switch 14 is closed with a snap 55 action, to preset the energizing circuit of winding 12^a of reversing switch 12 for completion upon engagement of contactor 39^a of switch 39 with the stationary contact 39^c. Contact 39^a will, however, remain in engagement with contact 39^b 60 so long as the load within container 5 rotates in the direction in which it was last driven by motor 6. When, during drifting of motor 6 and container 5 zero speed in the last direction of rotation thereof is reached, the loose or amorphous material or load within container 5 builds up in such manner that rotation of the latter in the reverse direction inherently results. As a consequence reverse movement of the armature of motor 6 is initiated, at which instant the contactor 39^a will be thrown by belt 39^e into engagement with contact 39^c.

An energizing circuit for the winding 12^a of reversing switch 12 is thus completed, said circuit 70 extending from line L¹ by conductors 24 and 34, 75

through contacts 22^c of relay 22, conductor 35 through contactor 39^a and contact 39^c of switch 39, conductors 42 and 43 through limit switch 14, conductor 44 through said winding 12^a of reversing switch 12, and by conductors 45, 38 and 28 to line L². Contacts 12^b, 12^c, 12^d of switch 12 are thus closed to effect reverse operation of motor 6 and cylinder 5 with the load contained in the latter. The reverse circuit connections for motor 6 are thus completed almost immediately after the self-reversing movement of container 5 which is incidental to the aforescribed character of the material contained within the latter, whereby excessive initial speed of the motor armature is avoided.

The aforescribed cycle of operations is repeated automatically until it is desired to shut down the entire system. Such a shut down may be effected at will by momentarily depressing the push button switch 31 which effects de-energization of the operating winding 22^a of relay 22 and opening of the contacts 22^b, 22^c of the latter, thus likewise insuring de-energization of one or the other of the windings 12^a or 13^a of reversing switches 12 and 13 (whichever one was active), and insuring against re-energization thereof pending momentary reclosure of push button switch 23 as aforescribed.

In the malting industry, the grain is delivered to and taken from the rotating drum while the drum is in motion through suitable chutes at the ends. Thus it is possible for the operator in normal operation to insure that the load is reduced suitably before depressing the stop button, to avoid excessive speed on the motor when driven by the load.

When desired an electromagnetically releasable brake may be employed,—the releasing winding thereof being adapted to be de-energized and the shoe thereof applied by spring or weight upon depression of the stop button 31,—thereby insuring against excessive overhauling action of the motor by the load.

What I claim as new and desire to secure by Letters Patent is:

1. In a control system of the character described, in combination, a substantially cylindrical container rotatable upon a horizontal axis, said container having therein an amount of amorphous material less than that required to completely fill the same, a reversible electric motor having a driving connection with said container, means for completing an energizing circuit for said motor whereby said container is rotated in one direction, means including a limit switch operable automatically to effect interruption of said motor circuit, said container being thereupon adapted to coast pending attainment of zero speed of rotation thereof in the direction aforementioned, whereupon the position of the material within said container serves to automatically initiate rotation of the latter in the reverse direction, a switch comprising a stationary contact and an oscillatable contactor, and means including a frictional driving connection between said container and said contactor whereby the latter is engaged with said contact immediately upon reversal of the former in the manner aforementioned, said contactor when engaged with said contact being adapted to effect completion of an alternative energizing circuit for said motor whereby the latter is adapted to drive said container in the reverse direction thereof so initiated, means including a second limit switch operable automatically to effect interruption of said alternative energizing circuit for the motor upon a predetermined number of rotations of said container in the direction thereof last mentioned, and means for positively interlocking said limit switches to insure closure of each upon opening of the other of same.

2. In a control system of the character de-

scribed, in combination, a substantially cylindrical container rotatable upon a horizontal axis, said container having therein an amount of amorphous material less than that required to completely fill the same, a reversible electric motor having a driving connection with said container, means for completing an energizing circuit for said motor whereby said container is rotated in one direction, means including a limit switch operable automatically to effect interruption of said motor circuit, said container being thereupon adapted to coast pending attainment of zero speed of rotation thereof in the direction aforementioned, whereupon the position of the material within said container serves to automatically initiate rotation of the latter in the reverse direction, a switch comprising a stationary contact and an oscillatable contactor, means including a frictional driving connection between said container and said contactor whereby the latter is engaged with said contact immediately upon reversal of the former in the manner aforementioned, said contactor when engaged with said contact being adapted to effect completion of an alternative energizing circuit for said motor whereby the latter is adapted to drive said container in the reverse direction thereof so initiated, and means including a second limit switch operable automatically to effect interruption of said alternative energizing circuit for the motor upon a predetermined number of rotations of said container in the direction thereof last mentioned.

3. In a control system of the character described, in combination, a substantially cylindrical container rotatable upon a horizontal axis, said container having therein an amount of amorphous material less than that required to completely fill the same, a reversible electric motor having a driving connection with said container, means for completing an energizing circuit for said motor whereby said container is rotated in one direction, means including a limit switch operable automatically to effect interruption of said motor circuit, said container being thereupon adapted to coast pending attainment of zero speed of rotation thereof in the direction aforementioned, whereupon the position of the material within said container serves to automatically initiate rotation of the latter in the reverse direction, a switch comprising a stationary contact and an oscillatable contactor, means including a frictional driving connection between said container and said contactor whereby the latter is engaged with said contact immediately upon reversal of the former in the manner aforementioned, said contactor when engaged with said contact being adapted to effect completion of an alternative energizing circuit for said motor whereby the latter is adapted to drive said container in the reverse direction thereof so initiated, means including a second limit switch operable automatically to effect interruption of said alternative energizing circuit for the motor upon a predetermined number of rotations of said container in the direction thereof last mentioned, and means for positively interlocking said limit switches to insure closure of each upon opening of the other of same.

4. In a control system of the character described, in combination, a substantially cylindrical container rotatable upon a horizontal axis, said container having therein an amount of amorphous material less than that required to completely fill the same, a reversible electric mo-

- 5 tor having a driving connection with said container, means for completing an energizing circuit for said motor whereby said container is rotated in one direction, means including a limit switch operable automatically to effect interruption of said motor circuit, said container being thereupon adapted to coast pending attainment of zero speed of rotation thereof in the direction aforementioned, whereupon the position of the
- 10 10 material within said container serves to automatically initiate rotation of the latter in the reverse direction, a switch comprising a stationary contact and an oscillatable contactor, means including a frictional driving connection between
- 15 15 said container and said contactor whereby the latter is engaged with said contact immediately upon reversal of the former in the manner aforementioned, said contactor when engaged with said contact being adapted to effect completion
- 20 20 of an alternative energizing circuit for said motor whereby the latter is adapted to drive said container in the reverse direction thereof so initiated, means including a second limit switch operable automatically to effect interruption of
- 25 25 said alternative energizing circuit for the motor upon a predetermined number of rotations of said container in the direction thereof last mentioned, means for positively interlocking said limit switches to insure closure and opening of each
- 30 30 upon opening and closure, respectively, of the other of same, and spring means associated with said limit switches to effect movements thereof with a snap action.
5. In a control system of the character described, in combination, a reversible electric motor, a load to be driven thereby in each direction, said load being of such character that it is self-reversing after coasting thereof in either direction as an incident to interruption of the motor
- 35 35 circuit connections, a pair of normally open electromagnetically operable switches, one of said switches being adapted upon energization and closure thereof to effect completion of a circuit for operation of said motor in one direction, a
- 40 40 limit switch operable upon a given number of rotations of said load to effect de-energization and opening of said last mentioned electromagnetically operable switch whereby said motor circuit is interrupted, said limit switch being simultaneously operable to preset an energizing circuit for the other of said electromagnetically operable switches for completion thereof upon self-reversal of the direction of rotation of said load after coasting of the latter, the means for effecting completion of said last mentioned circuit including a switch having a pair of stationary contacts and a pivoted contactor movable into engagement with one or the other of said contacts, depending upon the direction of rotation of said load, and said means including a frictional driving connection between said motor and said contactor.
- 45 45
- 50 50
- 55 55
- 60 60
- 65 65
- 70 70
- 75 75
6. In a control system of the character described, in combination, a substantially cylindrical container rotatable upon a horizontal axis, said container being adapted to receive an amount of loose material less than that required to completely fill the same, an electric motor having a positive driving connection with said container, a pair of normally open electromagnetically operable switches respectively adapted when closed to provide circuit connections for forward and reverse operation of said motor, means for insuring closure and opening of the respective switches in sequence to effect periodic reversal of

the direction of operation of said motor, said means comprising a pair of limit switches each having a pivoted contactor and an associated stationary contact, said contactors being mechanically interlocked to insure against simultaneous engagement thereof with said contacts, a pair of traveling nuts associated with said container and operable to sequentially effect opening of each of said limit switches while simultaneously effecting closure of the other of same upon like periods of rotation of said container in opposite directions respectively, each of said limit switches when closed being ineffective for completing an energizing circuit for its associated electro-magnetically operable switch pending operation of a direction-responsive switch common to said limit switches, said direction-responsive switch comprising a pair of spaced stationary contacts and an oscillatable contactor associated therewith, a frictional driving connection interposed between said container and said contactor whereby the latter is engageable with said stationary contacts alternately as an incident to reversal of the direction of rotation of said container, the arrangement being such that upon a given degree of coasting of said container in a given direction after interruption of the motor circuit connections the material within the container will be so positioned as to effect initiation of operation of said container in the reverse direction, such reverse operation of the container being adapted to effect engagement of the direction-switch contactor with one of its associated contacts whereby the limit switch then in closed position is rendered effective for completing an energizing circuit for its associated electromagnetically operable switch, whereby an alternative motor circuit is completed to effect positive driving of said container in the direction thereof last mentioned.

7. In a device of the character described, in combination, a reversible driving motor, a load to be rotatably driven thereby in each direction, said load being of such character that it is self-reversing after coasting thereof as an incident to interruption of the motor circuit connections, a pair of electromagnetically operable reversing switches for controlling the direction of operation of said motor, means for selectively effecting energization of said switches after each coasting period of said load to provide for substantially immediate positive driving of said load in the self-reversed direction of rotation thereof, said means comprising an oscillatable contactor, a pair of contacts to be selectively engaged thereby, and means providing a friction driving connection between said load and said contactor, whereby the latter is moved alternately from each extreme position thereof to the other only upon the respective self-reversing operations of said load.

8. In a protective device for a reversible electric motor driving a rotatable load which is self-reversing upon attainment of zero speed after rotation thereof in a given direction, in combination, a reversible electric driving motor, a pair of electromagnetically operable reversing switches adapted when energized selectively to alternately provide reverse circuit connections for said motor, a load to be driven by said motor, said load comprising a cylindrical container mounted upon a horizontal axis, said container having therein a quantity of amorphous material less than that required to entirely fill the same, means including manually operable means for initially effecting energization and closure of one or the other of said reversing switches to provide for rotation of

5 said load in one direction by said motor, means comprising a limit switch operable upon a predetermined number of rotations of said load to effect deenergization of said reversing switch with consequent interruption of the motor circuit connections, whereupon said motor and said load are adapted to coast to zero speed thereof in the direction aforementioned, switching means comprising a contact element movable in opposite 10 directions between given circuit controlling positions, means comprising a frictional driving connection between said rotatable load and said contact element, whereby said contact element is moved from one circuit controlling position thereof to the other as an incident to the self-reversing 15 operation of said load, and means adapted upon such movement of said contact element to automatically effect energization and closure of the other of said reversing switches, whereby immediate 20 reverse operation of said driving motor is effected, to thereby insure completion of the reverse circuit connections for said motor at substantially zero speed of said load in said reverse direction.

25 9. In a protective device for a reversible electric motor driving a rotatable load which is self-reversing upon attainment of zero speed after rotation thereof in a given direction, in combination, a reversible electric driving motor, a pair of 30 electromagnetically operable reversing switches adapted when energized selectively to alternately provide reverse circuit connections for said motor, a load to be driven by said motor, said load comprising a cylindrical container mounted upon a 35 horizontal axis, said container having therein a quantity of loose material less than that required to entirely fill the same, means including manually operable means for initially effecting energization and closure of one or the other of said reversing switches to provide for rotation of said load in one direction by said motor, means comprising a limit switch operable upon a predetermined number of rotations of said load to effect deenergization of said reversing switch with consequent 40 interruption of the motor circuit connections, whereupon said motor and said load are adapted to coast to zero speed thereof in the direction aforementioned, switching means comprising a contact element movable in opposite 45 directions between given circuit controlling positions, means comprising a frictional driving connection between said rotatable load and said contact element, whereby said contact element is moved from one circuit controlling position thereof to the other as an incident to the self-reversing 50 operation of said load, means adapted upon such movement of said contact element to automatically effect energization and closure of the other of said reversing switches, whereby immediate 55 reverse operation of said driving motor is effected, to thereby insure completion of the reverse circuit connections for said motor at substantially zero speed of said load in said reverse direction, said limit switch also acting upon a given number 60

of rotations of said load in said reverse direction to effect de-energization of the second mentioned reversing switch with consequent interruption of the motor circuit connections to provide for coasting of said motor and said load, and said contact element being operable upon self-reversing of said load to effect reenergization of said first mentioned reversing switch, whereby the operating cycle aforescribed is repeated. 5

10. In a protective device for a reversible electric motor driving a rotatable load which is self-reversing upon attainment of zero speed after rotation thereof in a given direction, in combination, a reversible electric driving motor, a pair of electromagnetically operable reversing switches 15 adapted when energized selectively to alternately provide reverse circuit connections for said motor, a load to be driven by said motor, said load comprising a cylindrical container mounted upon a horizontal axis, said container having therein a 20 quantity of loose material less than that required to entirely fill the same, means including manually operable means for initially effecting energization and closure of one or the other of said reversing switches to provide for rotation of said load in one direction by said motor, means comprising a limit switch operable upon a predetermined number of rotations of said load to effect de-energization of said reversing switch with consequent interruption of the motor circuit connections, 25 whereupon said motor and said load are adapted to coast to zero speed thereof in the direction aforementioned, switching means comprising a contact element movable in opposite directions between given circuit controlling positions, means comprising a frictional driving connection between said rotatable load and said contact element, whereby said contact element is moved from one circuit controlling position thereof to the other as an incident to the self-reversing 30 operation of said load, means adapted upon such movement of said contact element to automatically effect energization and closure of the other of said reversing switches, whereby immediate reverse operation of said driving motor is effected, 35 to thereby insure completion of the reverse circuit connections for said motor at substantially zero speed of said load in said reverse direction, said limit switch also acting upon a given number of rotations of said load in said reverse direction 40 to effect de-energization of the second mentioned reversing switch with consequent interruption of the motor circuit connections to provide for coasting of said motor and said load, said contact element being operable upon self-reversing of said load to effect re-energization of said first mentioned reversing switch, whereby the operating cycle aforescribed is repeated, and means including a normally closed manually operable switch adapted upon opening thereof to effect at 45 a full stop of said motor and the load driven thereby. 50

RALPH G. LOCKETT.
